[57] CLAIM

The ornamental design for a disposable blood sampling lancet, as shown and described.

DESCRIPTION

FIG. 1 is a side elevational view of a disposable blood sampling lancet showing my new design, with the other side views being identical;

FIG. 2 is a rear elevational view thereof;

FIG. 3 is a front elevational view thereof;

FIG. 4 is a perspective view thereof; and,

FIG. 5 is an exploded side view thereof, the broken line showing a needle tip for purposes of illustration only which forms no part of the claimed design.
